UNITED STATES PATENT OFFICE.

BERT KENNEDY, OF GLOVERSVILLE, NEW YORK.

STRIKING BAG.

Application filed May 26, 1925. Serial No. 33,002.

To all whom it may concern:

Be it known that I, BERT KENNEDY, a citizen of the United States, and a resident of Gloversville, in the county of Fulton and 5 State of New York, have made certain new and useful Improvements in Striking Bags, of which the following is a specification.

My present invention relates generally to exercising apparatus and more particularly 10 to what are known as striking bags, commonly used in connection with frames below which the bags are suspended for free movement against portions of the frame which in turn causes the bag to rebound for 15 the next blow. A rope is commonly used as the means of suspension for such bags, and the bag itself ordinarily includes an outer casing within which an inflatable flexible rubber inner casing is expanded, 20 the outer casing or bag proper having its upper smaller end provided with a laced closure, the lacing of which is accomplished after the inner casing is properly inflated. Across the upper end of the bag, an attaching 25 strap is extended with its ends sewed to the inner surface of the outer casing so that the suspension cord may be tied to this cross strap.

The result of this construction is that the 30 lower end of the suspension cord attached to the bag is rarely fixed securely in line with the axis of the bag so that it is very difficult to secure uniform and proper rebound of the bag from the frame and it is 35 not, in addition, easy to so tie the suspension cord as to get the bag at exactly the right height in order to properly strike the bag engaging portions of the frame.

Another disadvantage of the above mentioned ordinary construction is that the cross strap quickly wears and either breaks or pulls away from the casing of the bag.

It is the object of my present invention to eliminate the above disadvantages by the 45 provision of a top piece in connection with a striking bag, permitting the use of a laced side opening and of the complete closure of the reduced portion of the bag above the laced opening, as well as of the adjustable connection of the suspension cord in such manner as to insure its alinement with the axis of the bag.

In the accompanying drawing which illustrates my invention and forms a part of 55 this specification:—

Figure 1 is a perspective view illustrat-

ing a striking bag equipped with my improvements, and,

Figure 2 is a vertical section through the upper portion of the bag and through the top piece, as proposed by my invention and applied to the bag.

Referring now to these figures, and particularly to Fig. 1, I have shown portions of a frame for a striking bag including a rim 10 which the bag in its movement strikes. The bag is suspended in the frame by means of a cord or rope 11 and in order to insure even uniform rebound of the bag from the rim of the frame, this suspension cord or rope must be secured to the bag in line with the axis of the latter. I have generally indicated the bag at 12, provided in accordance with my invention, with a reduced upper portion 13 and with a laced side opening 14, through which the inflatable inner part is inserted in and removed from the casing of the bag, it being particularly noted that the reduced upper portion 13 of the bag is entirely closed above the laced opening 14, except for its upper central opening through which the top piece is in accordance with my invention clamped.

The top piece includes an inner disk 15 centrally from which a threaded tubular screw 16 upstands or outwardly projects, this screw extending through the upper opening of the bag and through an apertured outer disk 17 for the reception of a tapering clamping nut 18, the latter externally of the bag and adapted to clamp the edge of the bag around its opening between the disks 15 and 17.

Between the edge of the bag around its opening and the disks 15 and 17 are preferably employed leather or other washers 19 to insure better grip against the leather of the bag and also to avoid cutting through the adjacent portions of the bag, leather washers 19 being preferably of slightly greater diameter than the clamping disks 15 and 17.

The bore of the screw 16 is preferably extended through the disk 15 and will thus align with the bore of the clamping nut 18 through the latter of which the lower portion of the suspension cord 11 is readily introduced in order that it may be adjustably engaged and clamped by a set screw 20 threaded laterally through the nut 18 at one side as best seen in Fig. 2.

In this way it is obvious that by care in

the adjustment of the clamping parts in the first instance, the top piece of the bag may be located in axial alinement with the bag and in this way the suspension cord will necessarily attach to the bag in line with its axis so that proper rebounding movements of the bag from the rim 10 of the frame will be insured.

Equipped with my invention the striking bag as a whole will be stronger and more durable in addition to its adaptability to more effective manipulation in use and it is apparent that while attaining these many and decided advantages my invention does so with little additional cost, with little if any additional labor in placing the top piece in position in the first instance, and with much less trouble in properly maintaining the connection between the suspension cord and bag thereafter, as well as adjusting the bag with respect to the suspension cord when desirable or necessary.

I claim:—

1. A striking bag having a laced side

opening and a reduced upper end provided with an aperture in line with the axis of the bag, the said reduced upper end being closed between said side opening and said top aperture, and a top piece clamped through and around the top aperture, having a central bore in line with the axis of the bag to receive a suspension cord and including an external clamping nut having a cord gripping element.

2. A striking bag having a laced side opening and a reduced upper end provided with an aperture in line with the axis of the bag, the said reduced upper end being closed between said side opening and said top aperture, a top piece clamped through and around the top aperture, having a central bore in line with the axis of the bag to receive a suspension cord, and means carried by the top piece for adjustable engagement with the suspension cord in the bore of the top piece.

BERT KENNEDY.
